US00D477570S

(12) **United States Design Patent**
Zdinak et al.

(10) Patent No.: **US D477,570 S**
(45) Date of Patent: ** Jul. 22, 2003

(54) **OPTICAL COMMUNICATIONS DEVICE
HOUSING PORTION**

(75) Inventors: **Paul Zdinak**, Candia, NH (US);
Lawrence M. Kuba, Nashua, NH (US);
J. Derek Riemer, Westford, MA (US)

(73) Assignee: **Confluent Photonics Corp.**, Salem, NH (US)

(**) Term: **14 Years**

(21) Appl. No.: **29/142,796**

(22) Filed: **Jun. 1, 2001**

(51) LOC (7) Cl. **13-02**

(57) **CLAIM**

The ornamental design for the optical communications device housing portion, as shown and described.

DESCRIPTION

FIG. 1 is a perspective view of the optical communications device housing portion in accordance with a first embodiment of my design;

FIG. 2 is a front elevational view of the optical communications device housing portion in accordance with the first embodiment of my design;

FIG. 3 is a top plan view of the optical communications device housing portion in accordance with the first embodiment of my design;

FIG. 4 is a bottom plan view of the optical communications device housing portion in accordance with the first embodiment of my design;

FIG. 5 is a left side elevational view of the optical communications device housing portion in accordance with the first embodiment of my design;

FIG. 6 is a right side elevational view of the optical communications device housing portion in accordance with the first embodiment of my design;

FIG. 7 is a perspective view of the optical communications device housing portion in accordance with a second embodiment of my design, the left and right side elevational views thereof being the same as the views of FIGS. 5 and 6, respectively;

FIG. 8 is a front elevational view of the optical communications device housing portion in accordance with the second embodiment of my design;

FIG. 9 is a perspective view of the optical communications device housing portion in accordance with the third embodiment of my design, the top and bottom plan views thereof being the same as the views of FIGS. 3 and 4, respectively, and the left and right side elevational views being the same as the views of FIGS. 5 and 6, respectively;

FIG. 10 is a front elevational view of the optical communications device housing portion in accordance with the third embodiment of my design;

FIG. 11 is perspective view of the optical communications device housing portion in accordance with a fourth embodiment of my design, the left and right side elevational views thereof being the same as the views of FIGS. 5 and 6, respectively; and,

FIG. 12 is a front elevational view of the optical communications device housing portion in accordance with the fourth embodiment of my design.

The broken lines shown the environment in which the article is used and are not considered part of the design claimed.
